UNITED STATES PATENT OFFICE.

PHILMORE F. SPERY, OF CHICAGO, ILLINOIS, ASSIGNOR TO WILL FREEMAN, OF DES MOINES, IOWA.

EXTENSION TRUNK.

Application filed March 26, 1927, Serial No. 178,744

This invention relates to trunks of the type carried at the rear of motor cars for the transportation of luggage, tools, etc., and my main object is to form the trunk with an extensible portion, for use when greater capacity is desired.

A further object of the invention is to design the novel extension with a telescoping action, whereby to occupy a minimum 10 of space.

Another object of the invention is to construct the novel extension with fastening means of a simple and durable nature.

A final, but nevertheless important object 15 is to design the novel extension on simple and sturdy lines, for production at low expense.

With the above objects in view and any others that may suggest themselves from 20 the specification and claims to follow a better understanding of the invention may be gained by reference to the accompanying drawings, in which

Figure 1 is an elevation—partly broken 25 away—of the improved trunk, as viewed from the rear of the motor car or other vehicle on which it may be installed;

Fig. 2 is a magnified but fragmentary showing of the parts shown in section in 30 Figure 1;

Fig. 3 is an elevation of a detail;

Fig. 4 is a section of the trunk as extended; and

Fig. 5 is a similar view of the same as 35 collapsed.

Referring specifically to the drawings, 10 denotes the front wall of the trunk, 11 the side walls and 12 the bottom. The lid 13 is hinged at 14 from the front wall, and is 40 formed with beaded reinforcements 13^a to fit doubled flanges 11^a formed from the side walls 11 for better alinement with the latter.

The extension involves but the side walls and bottom of the trunk, and when considered with the latter, comprises an intermediate section 15 and a rear section 16, the intermediate section being adapted to telescope into the trunk, and the rear section into the intermediate section. When the assembly is telescoped, the rear wall 16^a of the sections 16 forms a closure for the rear end of the trunk, with which the lid may join as indicated in Figure 5, customary locking

devices 17 completing the closure whereby to hold the rear wall in place and give the 55 trunk the ordinary, short appearance.

In extending the trunk, the latter and the extension have cooperating guide elements to maintain the alinement of the extension sections with the trunk. Thus, the upper 60 edges of the sides 15 and 16 of the respective sections are formed with angular flange lengths 15^a and 16^a, respectively, which seat within each other and are relatively slidable; and the side walls 11 of the trunk carry on 65 their inner sides similar lengths 11^a—reinforced by suitable webs 11^b—to receive and guide the lengths 15^a. At the bottom, the trunk bottom 12 as well as the respective extension bottoms 15^b and 16^b are given a 70 common angular formation 18 to provide the necessary guidance along the bottom of the assembly. The extension section 15 is only designed to emerge about half-way from the trunk when fully extended; and so with the section 16 relative to the section 15. Substantial bearings are thus provided for the sections as against distortion or weakening from the weight or pressure of the contents. 75

The section 16 operates the section 15 by 80 means of pins 19 carried by the sides 16 and passing into horizontal slots 20 in the sides 15. The length of the slots is, of course, gaged to secure the proper distance of travel by the section 15 in either direction; and the 85 frontal edges of the sides 15 are formed with outward lugs 21 designed to abut inward stops 22^a formed from the rear edges of the side walls 11 of the trunk in case such sides creep in a rearward direction from 90 vibration, so that the section 15 cannot become separated from the trunk.

A top and bottom connection between the section 16 and the front wall 10 of the trunk is formed by a set of folding links 22 along 95 each wall. These are secured by loose rivets 23 to the parts connected, and have a locking pin 24 and seating notch 25 therefor to prevent complete unfolding when the section 16 has been fully extended. The links 100 will thus fold readily when the section is again closed, and without a tendency to bind. Owing to the intimate grouping and overlapping of the sections, the intermediate one need not have a medial bottom portion 105 as the rear section always overlaps the trunk

bottom. Hence, no opening would be created in the bottom of the extension by reducing the bottom of the intermediate section to the extent indicated at 26, where-
5 by metal may be economized.

The space indicated at 27 in Figure 2 is shown high for purposes of illustration, and to suggest that room must be left in the bottom of the trunk for the heads of the bolts
10 usually employed to fasten the trunk to the carrier or shelf which supports it.

The improved trunk is thus a structure of simple design and ample strength whether in normal or extended position. This is
15 necessary when it is desired to support the spare tire 28 from the trunk as shown. Having the rearmost position, the spare tire supplements or even supplants the bumper for protective purposes; also, where a
20 bumper is already carried, the spare tire is positioned where the bumper is not in its way.

While the extended trunk may—on account of the usually open state of its extension—be covered with a hood in the event of inclement weather, I have thought it preferable to provide a special cover 29 for the extension. As indicated more clearly in Figure 4, this cover is normally concealed
25 within the trunk cover 13 by hinging at the rear end, as indicated at 30, and retaining its front end in a spring clip 31 depending from the cover 13. Thus, when the trunk is extended the extension cover 29 may be
30 swung out and rested upon the extension as indicated by finely-dotted lines in Figure 4.

I claim:—

1. An extensible auto trunk comprising a main section, a hinged cover therefor, a section extensible from the main section, and a cover for the extensible section hinged from the free end of the main cover and foldable within the latter.
- 45 2. An extensible auto trunk comprising a main section with its rear end open, and a plurality of secondary sections rearwardly extensible from the open end of the main

section, such secondary sections being in a telescopic series with the main section. 50

3. An extensible auto trunk comprising a main section with its rear end open, and a plurality of secondary sections rearwardly extensible from the open end of the main section, such secondary sections being in a 55 series telescopically diminishing from the main section.

4. An extensible auto trunk comprising a main section with one end open, a cover for said main section, a plurality of secondary sections rearwardly extensible from the open end of the main section, such secondary sections being in a telescopic series with the main section, and a cover for the secondary sections normally foldable within the main 65 cover.

5. An extensible auto trunk comprising a main section, a hinged cover therefor, a section extensible from the main section, a cover for the extensible section hinged from 70 the free end of the main cover and foldable within the latter, and a spare tire carrier mounted on the end wall of said extensible section and movable therewith.

6. An extensible auto trunk comprising a main section with its rear end open, and a plurality of secondary sections rearwardly extensible from the open end of the main section, such secondary sections being in a telescopic series with the main section, the 80 rear most section of said secondary sections having a vertical wall adapted to cover the rear open end of said main section.

7. An extensible auto trunk comprising a main section having its rear end open, a 85 movable section having a rear wall to cover said open end, said movable section being adapted to form an extension of said main section, a hinged cover for said main section and a hinged cover for said movable section, said last cover being connected to said first cover and adapted to fold therebeneath when inoperative.

In testimony whereof I affix my signature.

PHILMORE F. SPERY.
